United States Patent Office.

THOMAS N. YOUNG, OF RICHMOND, INDIANA.

Letters Patent No. 96,296, dated October 26, 1869.

IMPROVEMENT IN STRAW-CUTTERS.

The Schedule referred to in these Letters Patent and making part of the same.

To all whom it may concern:

Be it known that I, THOMAS N. YOUNG, of Richmond, in the county of Wayne, and State of Indiana, have invented certain Improvements in Straw-Cutters; and I do hereby declare that the following is a full description thereof, reference being had to the accompanying drawings, making a part of this specification.

The first part of my invention relates to an improved mode of attaching and operating the knife, so as to produce an easy drawing cut, and give greater efficiency to the stroke.

The second part of my invention relates to the construction and arrangement of the feeding-mechanism, and devices for adjusting the same to feed more or less, as required.

The third part of my invention relates to an adjustable guide and compressing-board, that may be used either in conjunction or separately, as desired.

The object of the guide-board is to direct the straw between the feeding-rollers; and the invention consists in making it automatically adjustable.

The compressing-board retains the straw in a compact volume, after it leaves the feeding-rollers, until it is cut, and is adjusted automatically in the same manner as the guide-board.

Description of the Accompanying Drawings.

Figure 1, plate 1, is a perspective view of one form of my machine.

Figure 2, plate 1, is a sectional view, showing the guide-board and devices for compressing the straw between the feeding-rollers and the knife.

Figures 3 and 4, plate 2, are respectively front and side elevations of a machine differing from that shown in fig. 1, in that the shaft and balance-wheel are adjusted higher up, so as to be operated by a hand-crank instead of a treadle, as in the first instance.

The cutter-box A is supported upon any suitable frame, and is provided with two feeding-rollers, c d.

The journals of the lower roller c are adjusted in stationary boxes, while those of the upper roller d are placed in vertical slots in the sides of the cutter-box A.

E represents a broad belt or piece of canvas, that passes over the lower feeding-roller c, and a tension-roller, f, its upper surface forming a portion of the bottom of the cutter-box.

The knife G is pivoted, at one end, to the swinging arm P, and at the other, to the head-block F, that slides in the inclined groove I.

The head-block consists of a block of metal, by preference, centrally perforated, for the reception of a stud or wrist, by which it is attached to the knife, and having narrow strips or tongues formed on its edges, which hold and guide it in the inclined groove, the ways forming the latter being provided with flanges extending over such strips.

Motion is imparted to the head-block F, and thence

to the knife, by means of a pitman, J, attached to a crank upon the shaft U.

Should it be desirable, the shaft U, with the balance-wheel W and pitman J, may be dispensed with, and the machine operated by means of a simple lever, that is bolted to the head-block F, (as indicated by dotted lines in fig. 1,) the lower end of said lever being held in position by a fulcrum-pin, m, that works in a slot, to allow of lateral play.

The feeding-rollers are actuated by the head-block F, that raises one end of the pivoted bar D, thereby withdrawing the pawls n n, and turning the ratchets r v upon the said rollers.

The extremity of the bar D is upheld by a hook, L, that passes through a fixed support on the frame, and is provided with thumb-nut, whereby it may be adjusted to hold the bar at any height required. By means of this arrangement, the pawls n n may be made to retrace one, two, or more teeth upon the ratchets, thus varying the length of the feed as required.

The springs a a, figs. 1 and 2, are attached by bolts to the board H, that extends across the top of the cutter-box A.

Attached to the board H are two posts, l l, that stand upon the journals of the feeding-roller d, in slots in the sides of the cutter-box, and are elevated and depressed with said journals.

Near the front edge of the board H is attached a compressing-board, Y, that is provided with a bevelled foot, X, and is designed to keep the ends of the straw from rising after passing the feeding-rollers.

The guide-board K, also attached to the board H, serves to direct the straw so that it may readily enter between the rollers.

When the roller d is elevated by the straw passing beneath it, the guide-board K and compressing-board Y, (being connected through the posts l l with journals of said roller,) are automatically elevated and adjusted to the proper height.

Claims.

I claim—

1. The sliding head-block F and inclined groove I, constructed as described, and used in combination with the knife G and swinging arm P, in the manner and for the purposes specified.

2. The pivoted bar D, pawls n n, adjusting-hook L, and head-block F, when constructed and operated in combination, substantially as described.

3. The combination of the feed-rollers with the springs a, the guide-board K, and compressing-board Y, when constructed and arranged to operate as described.

THOMAS N. YOUNG.
